ANTENNA STRUCTURE

Nathan Marchand, New York, N. Y., assignor to
Federal Telephone and Radio Corporation, New
York, N. Y., a corporation of Delaware

Application July 22, 1944, Serial No. 546,117

7 Claims. (Cl. 250—11)

1

This invention relates to antenna structures particularly those having directional radiant action characteristics.

An object of the present invention is the provision of an improved antenna structure particularly one having directional radiant action characteristics.

Another object of the present invention is the provision of an antenna structure of the type described which is extremely compact and rugged.

A further object of the present invention is the provision of an improved antenna structure in which the radiating elements include loops formed from concentric line conductors and which depend for their operation on the coupling between the inner conductor and the outside of the outer conductor of said concentric lines provided by gaps in the outer conductor.

Another object of the present invention is the provision of an improved antenna structure employing a plurality of horizontally disposed loops providing plane polarized radiant action patterns of the crossed figure of eight type and which is particularly adapted for direction finding purposes.

A still further object of the present invention is the provision of an antenna structure of the type hereinbefore described which may be directly supported on a metallic mast or other supporting structure without the use of insulators.

Other and further objects of the present invention will become apparent and the foregoing will be best understood from the following description of embodiments thereof, reference being had to the drawings in which:

Fig. 1 is a bottom plan view of a preferred form of antenna structure in accordance with the present invention;

Fig. 2 is a front elevational view in perspective of the antenna structure of Fig. 1 and includes a schematic diagram of the connections of said antenna with a signal system;

Fig. 3 is a front elevational view of a modified form of antenna structure in accordance with the present invention; and

Fig. 4 illustrates substantially the radiant action pattern of said antenna structures.

In the antenna structure of Figs. 1 and 2, the radiant acting elements consist of four loops 1, 2, 3 and 4, each of the concentric line type having an inner conductor 5 and an outer conductor 6.

Each of the loops 1 through 4 is horizontally 55

2

disposed in the same horizontal plane and is substantially in the form of an isosceles triangle having equal sides 7 and 8; 9 and 10; 11 and 12; and 13 and 14 respectively. Triangular loops 1 through 4 are symmetrically disposed around a central point and have their apices arranged adjacent each other at the center of the array with their bases 15 through 18 forming a substantially closed, square geometrical pattern for the array.

Adjacent sides of adjacent triangular loops run alongside and abut each other. To insure that the electrically effective lengths of such adjacent sides are equal and to provide a rugged structure, said adjacent sides are preferably connected along their length as, for example, by soldering, and each pair of adjacent sides is enclosed in a close-fitting metallic shield 20. The shields 20 are all of the same length so that the array is electrically balanced. Each of the shields 20 extend from a central metallic junction box 21 to one of a plurality of metallic junction boxes 22, each of said junction boxes 22 being arranged at the outer end of a pair of adjacent sides such as, for example, sides 10 and 11. The adjacent sides are crossed over within junction boxes 22, and are horizontally coplanar outside of said boxes.

Each of the loops 1 through 4 is open at its inner end, that is, at its apex, and opposite loops are connected to each other in parallel. More specifically, the inner ends of sides 7 and 8 of loop 1 are not connected to each other but instead, said inner ends are connected by connectors 23 and 24 within junction box 21 to the inner ends of sides 12 and 11 respectively of loop 3, which is opposite loop 1. Likewise the inner end of sides 9 and 10 of loop 2 are connected by connectors 25 and 26 respectively to the inner ends of sides 14 and 13 respectively of loop 4. Connectors 23 through 26 each consist of a short piece or link of concentric line arranged within junction box 21.

Each of the connectors 23 through 26 has its outer conductor open at the center thereof to enable connection of said connector to a transmission line, connectors 23 through 26 being connected respectively to concentric transmission lines 27 through 30. Transmission lines 27 through 30 are symmetrically arranged within a metallic shield or mast 31 extending from the bottom of central junction box 21 and which also serves as a support for the loop array. Lines 27 and 28 go to one load or energizing source and lines 29 and 30 go to another load or energiz-

ing source. Thus lines 27 and 28 form one dual transmission line, and lines 29 and 30 form another.

Said loads or sources may consist of goniometer field coils 32 and 33 whose cooperating search coil 34 may be in turn connected to a translating device 35 which is in turn coupled to a signal device 36. If the system illustrated consists of a direction finding system, then the signal device would be an indicator whereas if the system is used as a beacon device, then the signal device would consist of some source of modulating signals usually of audio frequencies.

To enable the loops to function as radiant acting elements, a gap or break is provided in the outer conductor 6 of each of the loops, that is, the outer conductors of loops 1 through 4 are provided with gaps 37 through 40 respectively. These gaps serve to couple the inner conductor 5 to the outer surface of the outer conductor 6 at said gaps. While the size of the gaps may be varied, it is preferred that they be made as small as possible, but not so small that the capacity between the ends of the outer conductor across said gap will effectively short said gap at the radio frequency used.

By positioning the gaps at a point in each loop directly opposite the portion of said loop arranged within the central junction box 21, said latter portion will be at a null point of potential on said loop and therefore will not have to be insulated from said junction box and its supporting mast 31. Thus, for example, gap 37 is directly opposite said connector 25 of loop 1 and said connector is at a null potential point in relation thereto. Thus the connector 25 does not have to be insulated from the central junction box 21. It will be seen that in this arrangement, the gap 37 is directly opposite the apex of the triangular configuration of loop 1 and is located at a mid-point of the base of this triangle. Gaps 38, 39 and 40 are similarly arranged.

The arrangement heretofore described in connection with Figs. 1 and 2 has a radiant action pattern sharply plane polarized and in the system described, this polarization is horizontal. The current flows in opposite loops in opposite clockwise directions, that is when the current runs clockwise around loop 1 it runs counterclockwise around loop 3, and when it runs clockwise around loop 2 it runs counterclockwise around loop 4. The radiant action pattern produced is substantially as shown in Fig. 4 and is of the crossed figure of eight type. In order to prevent distortion of the pattern by various interfering influences such as, for example, the vertical components of downwardly inclined waves, it is preferred that the dimensions of the radiant action portions of the structure be as small as possible for the sensitivity or pick-up required. It is preferred, for example, that the sides of the array, more specifically the length of the base of each of the triangular loops, be less than one-eighth of the shortest wavelength to be received, while the total length of each loop measured around its perimeter should be less than one-quarter wavelength. The height of the mast above ground is not critical as far as it affects the radiant action pattern and may be, for example, from one-half wavelength to a number of wavelengths.

The arrangement shown in Figs. 1 and 2 is adapted primarily for horizontally polarized radiant action. In certain instances, it may be desirable also to provide for vertically polarized ra-

diant action also, while still providing a crossed figure of eight radiant action pattern. This may be accomplished by providing vertical dipoles adjacent each of the gaps in the following manner.

Referring now to Fig. 3 in which the numerals applied to the elements illustrated in Figs. 1 and 2 are applied to the same elements in Fig. 3, a dipole is arranged at gap 37 with the upper member 41 of the dipole on the left side of the gap and the lower member 42 on the right side of the gap. At the opposite gap 38 the lower member 43 of a dipole is arranged on the left side of the gap while the upper member 44 is arranged at the right side of the gap. It will thus be seen that the dipoles are oppositely arranged on opposite sides of the structure so that they are 180° out of phase and yield a cross-over of the electrical connections, thus providing a figure 8 radiant action pattern. In similar fashion, dipoles are arranged adjacent gaps 39 and 40 with the upper and lower member of the dipole at gap 39 oppositely disposed in relation to the upper and lower member at gap 40. The dipoles thus produce vertically polarized radiant action patterns of the crossed figure of eight type which patterns will coincide with those produced by the horizontally polarized loops.

While I have described my invention in connection with the details of specific structures, it will be obvious that modifications in these details may be made without departing from my invention. For example, the junction boxes 22 may be dispensed with. Instead of having four transmission lines 27 through 30 going down through the mast 31, connectors 25 and 26 may be connected to one balanced dual transmission line and connectors 23 and 24 may be connected to another balanced dual transmission line. Other modifications within the scope of my invention will occur to those versed in the art, from the foregoing description.

Accordingly, while I have described above the principles of my invention in connection with specific apparatus and particular modifications thereof, it is to be clearly understood that this description is made only by way of example and not as a limitation on the scope of my invention as set forth in the objects and the claims.

I claim:

1. A radio antenna structure providing a crossed figure of eight radiant action pattern for plane polarized waves comprising four symmetrical loops disposed in the same plane immediately adjacent each other around a central point to form a substantially closed geometrical pattern, each of said loops being open adjacent said central point to provide a pair of open ends, the open ends of each pair of opposite loops being connected in parallel to each other and to a dual transmission line.

2. A radio antenna structure according to claim 1 wherein the loops are each substantially in the form of a triangle and are mounted with their apices adjacent said central point, their sides contiguous and their bases forming a substantially closed square.

3. A radio antenna structure according to claim 1 wherein each of the loops is formed of a concentric line having an inner and outer conductor, and the outer conductor of each loop has a gap therein to effectively couple the outside of said outer conductor to said inner conductor.

4. A radio antenna structure according to claim 1 wherein each of the loops is formed of a concentric line having an inner and outer conduc-

tor, and the outer conductor of each loop has a gap therein at a point of said loop substantially equally spaced around said loop from said central point.

5. A radio antenna structure according to claim 1 wherein each of the loops is formed of a concentric line having an inner and outer conductor, and the outer conductor of each loop has a gap therein at a point of said loop opposite said central point, and a conductive support member 10 on which said loops are directly supported at portions of said loops adjacent said central point.

6. In combination with a radio antenna structure according to claim 1, a goniometer having

two coils at right angles to each other, each of said coils connected with one of said dual transmission lines, and a search coil, a translating device connected to said search coil, and a signal device connected with said translating device.

7. In a direction finder, the combination with a radio antenna structure according to claim 1, of a goniometer having two coils at right angles to each other, each of said coils connected with one of said dual transmission lines, and a search coil, a receiver connected to said search coil and a visual indicating device connected with said receiver.

NATHAN MARCHAND.
